UNITED STATES PATENT OFFICE.

AUGUST LUSSKY, OF LOUISVILLE, KENTUCKY.

ATTACHMENT FOR WHEELBARROWS.

968,248.

Specification of Letters Patent. Patented Aug. 23, 1910.

Application filed March 21, 1910. Serial No. 550,673.

To all whom it may concern:

Be it known that I, AUGUST LUSSKY, a citizen of the United States, residing at Louisville, in the county of Jefferson and 5 State of Kentucky, have invented certain new and useful Improvements in Attachments for Wheelbarrows; and I do hereby declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to new and useful improvements in attachments to wheelbarrows and affording means whereby the wheel may conveniently pass from one level 20 to a higher or over an obstruction and comprises a simple and efficient device adapted to be permanently attached to the wheelbarrow.

The invention comprises various details 25 of construction and combinations and arrangements of parts which will be herein-after fully described and then specifically defined in the appended claims.

My invention is illustrated in the accompanying drawings, in which:—

Figure 1 is a perspective view showing the device adjusted for use. Fig. 2 is a side view showing the movable member upon which the wheel travels held back in a position out of use. Fig. 3 is a transverse sectional view on line 3—3 of Fig. 2, and Fig. 4 is a detail perspective showing the rod and loops adapted to be supported by the axle of the wheel.

Reference now being had to the details of the drawings by letter, A designates the frame of a wheelbarrow of the usual construction having an axle B upon which the wheel C is mounted, the ends of said axle 45 being journaled in suitable bearings in the rails of the wheelbarrow.

D designates the cross-piece of the wheelbarrow which is notched at D', and E designates a hook which is mounted in the cross-piece adjacent to the marginal edge of said recess.

F, F designate wires which are bent to form elongated loops supported upon the axle, one upon either side of the wheel, and 55 G designates a bolt which is supported in the contracted ends of said loops, as shown.

H designates a board which may be of any suitable size and is provided with a recess I formed in one end and an elongated slot K formed transversely through the board, said slot being adapted to receive said bolt which has a play therein. A screw eye N is fastened to the rear portion of said board and is adapted to engage said hook to hold the board in the recess D' when said board is not in use, the edges of the recess preventing a lateral swinging movement of the board when thus held out of use. When the board is adjusted in the position shown in Fig. 2 of the drawings, it will be noted 70 that the wheel will turn in the recess I without interference to the board.

The operation of my device will be readily understood and is as follows:—The board being normally held to the wheelbarrow 75 frame in the manner shown in Fig. 2 and, in the event of it being desired to utilize the same for wheeling the device up a curb or over an obstruction, the eye N is detached from the hook upon the frame, the wheel of 80 the device raised in any suitable manner, as by tilting the frame upon its legs, to allow the board to be inserted and the wheel in the position shown in Fig. 1, after which the wheel barrow may be pushed forward, the wheel 85 engaging the slot in the end of the board and allowing the wheel to make a partial revolution, the bolt G moving in the slot K. After the wheelbarrow has passed upon the higher level, the board may be 90 fastened back to its normal position as shown in Fig. 2.

What I claim to be new is:—

1. An attachment for wheelbarrows comprising, in combination with the wheelbarrow, a board pivotally connected thereto and forming an inclined bridge up which the wheel is adapted to travel.

2. In combination with the frame of a wheelbarrow having an axle and a wheel 100 thereon, elongated loops through which said axle passes, and a board fastened to said loops and forming a bridge up which the wheel is adapted to travel.

3. In combination with the frame of a wheelbarrow having an axle and a wheel thereon, elongated loops through which said axle passes, a bolt connecting corresponding ends of said loops, and a board having an elongated slot therein through which said 105 bolt passes and is adapted to have a play.

4. In combination with the frame of a

wheelbarrow having an axle and wheel thereon, elongated loops through which said axle passes, a bolt connecting corresponding ends of said loops, a board having an elongated slot therein through which said bolt is adapted to have a play, one end of said board being slotted to receive the wheel.

5. In combination with the frame of a wheelbarrow having an axle and a wheel thereon, elongated loops through which said axle passes, a bolt connecting corresponding ends of said loops, a board having an elongated slot therein through which said bolt is adapted to have a play, one end of said board being slotted to receive the wheel, an eye upon the rear portion of said board, a hook fastened to the wheelbarrow and adapted to engage said eye, a cross-piece of said wheelbarrow having a recess adapted to hold the rear end of the board from lateral movement.

10. In combination with the frame of a wheelbarrow having an axle and a wheel thereon, elongated loops through which said axle passes, a bolt connecting corresponding ends of said loops, a board having an elongated slot therein through which said bolt is adapted to have a play, one end of said board being slotted to receive the wheel, an eye upon the rear portion of said board, a hook fastened to the wheelbarrow and adapted to engage said eye, a cross-piece of said wheelbarrow having a recess adapted to hold the rear end of the board from lateral movement.

15. In combination with the frame of a wheelbarrow having an axle and a wheel thereon, elongated loops through which said axle passes, a bolt connecting corresponding ends of said loops, a board having an elongated slot therein through which said bolt is adapted to have a play, one end of said board being slotted to receive the wheel, an eye upon the rear portion of said board, a hook fastened to the wheelbarrow and adapted to engage said eye.

6. In combination with the frame of a

wheelbarrow having an axle and a wheel 20 thereon, elongated loops through which said axle passes, a bolt connecting corresponding ends of said loops, a board having an elongated slot therein through which said bolt is adapted to have a play, one end of said board being slotted to receive the wheel, an eye upon the rear portion of said board, a hook fastened to the wheelbarrow and adapted 25 to engage said eye, a cross-piece of said wheelbarrow having a recess adapted to hold the rear end of the board from lateral movement.

In testimony whereof I hereunto affix my signature in the presence of two witnesses.

AUGUST LUSSKY.
